US0D1020421S

(12) **United States Design Patent** (10) **Patent No.:** **US D1,020,421 S**
(45) **Date of Patent:** **** Apr. 2, 2024**

(54) **LITHIUM BATTERY-POWERED CHAINSAW**

(71) Applicant: **JINHUA BOCHAO TOOLS CO., LTD**, Zhejiang (CN)

(72) Inventor: **Hongfeng Du**, Zhejiang (CN)

(**) Term: **15 Years**

(21) Appl. No.: **29/816,142**

(22) Filed: **Nov. 19, 2021**

(30) **Foreign Application Priority Data**

Aug. 25, 2021 (CN) 202130554571.0

CLAIM

The ornamental design for a lithium battery-powered chainsaw, as shown and described.

DESCRIPTION

FIG. 1 is a front elevational view of a lithium battery-powered chainsaw showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof; and,

FIG. 7 is a perspective view thereof.

The broken lines in the drawings illustrate portions of the lithium battery-powered chainsaw and form no part of the claimed design.

1 Claim, 7 Drawing Sheets
